UNITED STATES PATENT OFFICE.

WILLIAM G. LIEBIG, OF DETROIT, MICHIGAN.

BRISTLE-FEEDING MECHANISM.

1,203,212.

Specification of Letters Patent.

Patented Oct. 31, 1916.

Application filed March 26, 1915. Serial No. 17,193.

To all whom it may concern:

Be it known that I, WILLIAM G. LIEBIG, a citizen of the United States, residing at Detroit, county of Wayne, State of Michigan, have invented a certain new and useful Improvement in Bristle-Feeding Mechanism, and declare the following to be a full, clear, and exact description of the same, such as will enable others skilled in the art to which it pertains to make and use the same, reference being had to the accompanying drawings, which form a part of this specification.

This invention relates to bristle-feeding means for brush making machines, and has for its object improvements designed to secure greater uniformity in the positioning, alining, and compacting of the mass of bristle material, before tufts of the desired size are removed by the notched edge of the tuft-gathering and carrying member.

The word "bristles" as used is of course intended to cover all kinds, either fiber, animal, or wire.

25 In the drawings:—Figure 1 is a front elevation of a brush making machine, with its bristle-feeding box in position adjacent thereto. Fig. 2 is a cross section of the box, with some parts shown in elevation, along 30 the line 2—2 of Fig. 1. Fig. 3 is a plan view of the box with a portion of the cover broken away. Fig. 4 is a detail side elevation, partly in section.

11 indicates the frame of the machine 35 whose various parts are driven from the several cam wheels 12, which are mounted upon the shaft 13, the several slides, by which movement is communicated to the various parts of the machine, engaging in 40 tracks in these cams. One of these actuating slides drives the bristle picker or carrying member 15, oscillating it about its pivot 16 as a center, so that its notched periphery 17 engages against the forward edge of a mass 45 of bristles 18, stored in the box 19. As the details of the tuft-handling mechanism form the subject matter of various patents already issued to me, and of applications now pending, no further detailed description 50 need be here attempted as to these parts.

The bristles stored in the box 19 are fed forward toward the edge of the tuft-gatherer, by the constant weight-actuated pressure of the follower 20, which carries 55 the plate 21 on its forward edge. For many classes of bristle material, particularly the

rougher grades, the compressive influence of this follower and its box is entirely sufficient. But for use with fine bristles, and especially with lengths of fine wire, now 60 much used for this purpose, it is my experience that a greater compressive force on the bristles, and one acting in a variety of directions thereon, is necessary to hold them in such position that tufts of the desired 65 size may be seized at each sweep of the tuft-gathering member without displacement from their proper alinement, and that the bristles that remain in the box to be removed by subsequent sweeping of the picker 70 member are similarly held against displacement. To accomplish this, I provide in the first instance a pivoted floor piece 24 for the forward part of the box, which is yieldingly forced upward at its forward end by 75 means of a leaf spring 25, whose pressure can be adjusted by means of the milled screw 26. I also supplement this containing influence upon the mass of bristles at their forward edge, by means of the beveled 80 catch piece 27, which is yieldingly supported in the bracket 28 by means of the spring 29, in such position that the beveled edge is slightly above the bottom of the mass of bristles engaged by the curved edge of the 85 picker member.

To resiliently hold the mass of bristles against upward displacement when the upward sweep of the picker member results in filling the slot 17^a, I provide on one edge of 90 the bristle box, a long leaf spring or bar 30, whose rear end is pivoted in a post 31, and whose central portion is adapted to engage in the horizontal slotted top of the auxiliary post 32. If desired, these springs 30 95 may be of unequal length, thus necessitating only one auxiliary post 32. Similarly positioned along the other edge of the bristle box, though preferably not quite as long as the spring 30, is a second spring 30^a. When 100 swung to a position lengthwise of the box, these leave the forward free end of the springs resiliently placed upon the top of the mass of bristles 18 in such a way and to such a degree as to prevent the escape of 105 any bristles not seized by, and included in, the slot 17^a. These spring pieces 30 and 30^a consequently serve not only to hold the bristles from positive displacement by the picker, but also from being thrown out of 110 alinement from their position across the box. There is thus exerted upon the for-

ward edge of the mass of bristles an upward and a downward movement which compresses the mass to such a degree as to make a firm body upon which the slot 17^a 5 in the picker or tuft-gatherer 15 can act, thus resulting in uniformity in the size of the tufts seized at each oscillation of the tuft-gatherer. To further secure the proper alinement of the bristles, there is provided 10 on one edge of the box a horizontally acting leaf spring 33, which is inclosed in the top of the post 34 in such a way that the forward free end of each spring may act upon the ends of the mass of bristles as stored 15 in a way to keep them properly alined lengthwise of one another, thus bringing it about that each tuft of bristle is seized by the picker and bent when being stapled into the brush back at its exact center, thus securing uniformity in the lengths of the 20 tufts, and rendering trimming thereof when the brush is completed either wholly unnecessary or only slightly necessary. There may also be provided, if desired, a similarly 25 acting spring 33^a on the other edge of the box, to engage the other ends of the bristles from those engaged by the spring 33.

If the bristles used are of wire, it may of course be assumed that they will be of 30 uniform diameter throughout their length, so that both edges of the mass stored within the box 19 are of equal extent when the mass is compressed by the action of the follower member 20. When, however, either 35 fiber or hair bristles are used, the slightly tapering character of each contributes to cause an inequality in the extent of the mass lengthwise of the box on one side and on the other. If the plate 21 carried on the 40 end of the follower 20 were rigidly positioned straight across the box 19 which would be entirely satisfactory in the case of wire bristles, this would result in the presentation of the fiber or hair bristles at the 45 forward edge of the pile to the action of the picker or tuft-gatherer 15 at an angle other than the right angle which is necessary for the formation of a neat and even lengthened tuft. To avoid this I provide for an adjustable attachment of the plate 21 to the follower 20 through the medium of the ears 50 23 and 23^a and the screw 22; the plate can thus be set at an angle corresponding to the rearmost edge of the mass of bristles when 55 the bristles located at its forward edge, under equal compression, are located straight across the box, transversely of the line of movement of the follower member and similarly in perpendicular position to the plane 60 of travel of the tuft-gatherer 15 whose notched edge engages them.

What I claim is:—

1. Feed mechanism for brush material, comprising a storage box, a steady pressure 65 follower member for forcing material

stored therein toward the delivery end thereof, a resiliently supported bottom piece for raising the material at the outer end of the storage pile slightly above the bottom of the storage box; and a pair of adjustable spring 70 members adapted to engage the top of the mass of material to be withdrawn from the storage box, to prevent undesired bending and displacement thereof when engaged by a tuft-removing member. 75

2. In combination with a storage box, a follower member slidably engaging lengthwise thereof to evenly press material stored therein toward the delivery end thereof, and a pair of oppositely acting spring retaining 80 members adapted to compress the material at the outer edge of the storage pile to prevent the escape or undesired displacement of the material remaining when a tuft of bristles is withdrawn by the action of an engaging external member. 85

3. In combination with means for feeding forward a mass of alined bristles the engaging forward portion thereof being angularly adjustable, a pair of spring members adapted to engage the end portions of the bristles at the top of the forward portion of the mass to prevent their unintended displacement when frictionally engaged by a tuft-removing member, and spring means engaging the forward portion of the pile from beneath, to prevent the downward escape of the bristles under the influence of the reverse movement of the tuft-removing member. 95

4. In combination with a tuft-removing member, means for forcing a mass of stored bristles against the engaging periphery thereof while compensating for possible variations in the thickness of the mass from one side to the other, spring means for yieldingly holding the bottom of the pile of bristles against unintended displacement when frictionally engaged by the downward movement of the tuft-removing member, and spring members engaging the ends of the bristles adjacent said tuft-removing member to resist the displacing influence of the tuft-removing member on its upward travel. 100 105 110

5. The combination of a storage box, a follower member for forcing a mass of bristles stored therein toward the delivery end thereof, spring means for engaging the forward portion of the mass of bristles to prevent their unintended displacement when acted upon by a tuft-removing member, and alining members adapted to act upon the ends of the bristles to insure uniformity in the relative lengthwise position of the individual bristles to one another. 115 120 125

6. Means for feeding brush material to a tuft-removing member, comprising a storage box, a follower member adapted to force a mass of bristles toward the delivery end of the box, and adjustable means for exert- 130

ing a yielding pressure from opposing directions upon the bristles about to be engaged by the tuft-removing member to prevent their undesired displacement.

- 5 7. In combination with a storage box, a follower member engaging lengthwise thereof to force a stored mass of bristles toward the delivery end thereof, and an angularly adjustable plate carried on the forward end
10 of said follower member, whereby compensation may be effected for variations in the thickness of the mass of bristles from one side to another, thereby permitting the presentation of the foremost portion of the mass
15 to the action of an external tuft-removing member in substantially perpendicular position to the plane of travel thereof.

8. In combination with a storage box a follower member adapted to exert pressure
20 upon a stored mass of bristles, an adjustable plate carried thereby adapted to engage the rearmost portion of the mass of bristles to compensate for the possible tapering character
25 of the mass of bristles and to present the bristles at the foremost edge of the pile in a substantially perpendicular position to the line of movement of the follower member.

9. Feed mechanism for brush material,

comprising a containing box having an open delivery end across which a tuft-removing member is adapted to engage, a pair of oppositely acting compressive members adapted to act upon that portion of the mass of stored bristles about to be engaged by the tuft-removing member, and an adjustable follower member adapted to exert a steady pressure upon the mass of bristles to force them toward the delivery end of the box and between said compressive members.

10. In combination with a feed box having
an open delivery end, a plurality of series
of resilient and oppositely acting bristle-
engaging members adapted to aline and com-
press the mass of bristles as the delivery end
of the box is reached, and a steady pressure
follower member having an angularly ad-
justable engaging end adapted to force the
mass of bristles toward said open end and
into the sphere of influence of said alining
and compressing members.

In testimony whereof I sign this specification in the presence of two witnesses.
